UNITED STATES PATENT OFFICE.

ELEAZER KEMPSHALL, OF NEW BRITAIN, CONNECTICUT.

HEEL FOR BOOTS OR SHOES.

SPECIFICATION forming part of Letters Patent No. 376,824, dated January 24, 1888.

Application filed July 8, 1886. Serial No. 207,386. (No model.)

To all whom it may concern:

Be it known that I, ELEAZER KEMPSHALL, a citizen of the United States, residing at New Britain, in the county of Hartford and State 5 of Connecticut, have invented certain new and useful Improvements in Heel-Protectors, of which the following is a specification.

My invention relates to that class of heel-protectors that are inserted into the heel, and 10 the object is to provide a protector which shall be securely held in place without fastenings, and shall be clear of the objectionable features of those heretofore used by concealing them in the boot-heel; and it consists in 15 the construction hereinafter described, and more particularly pointed out in the claim.

Referring to the accompanying drawings, forming a part of this specification, Figure 1 is a plan view of the under side of the same. 20 Fig. 2 is an enlarged view showing a vertical section of one of my protectors. Fig. 3 is a top view of the same. Fig. 4 is a vertical section through the lower lift and protector. Fig. 25 5 is a similar view showing a solid protector inserted in the lift.

Similar characters designate like parts in all the figures of the drawings.

My improvements are designed especially for the finer and more expensive kinds of 30 ladies' boots, in which heel-protectors are not now usually inserted, because they detract from the finished appearance of the boot. To overcome this objection the heel B is made of several layers or lifts of leather in the ordinary manner; or, if desired, a wooden or leather-covered wooden heel may be used having one 35 lift of leather forming the bottom thereof, in which my protector is inserted.

H represents the lower lift of the heel, which 40 is bored into from the upper side in one or more places, as may be desired, and the protector 6 inserted therein, so that it will reach nearly through the lift, the insertion of the

protector by a suitable tool causing a slight raised surface, 4, on the under side of the lift 45 beneath the protector. This raised surface 4 indicates to the workman the position of the concealed protector 6, and assures the purchaser that there are protectors in the heels of the boots.

By the insertion of my protector the under surface of the lift is disturbed so little that the whole surface can be polished at the same time and given a uniform finish, which could not be done were the lift bored through and the protector made to protrude.

My protector consists of a hollow conical stud or ring, and is intended to be filled with leather or other material, 7, composing the lift, as shown in Figs. 2, 3, and 4. In this case, 60 when the heel is worn away to the line a a, the heel-protector is exposed and resists further rapid wear, while the central core or filling, 7, wears away with the lift, leaving the narrow rim of the hard-metal stud slightly projecting, to catch into depressions in the foot-way or road to resist any tendency of the heel to slip. In this form the conical shape of the protector prevents its coming out or being lost when in the heel.

The protectors may be other than circular in form, if desired, as rectangular, polygonal, or of other desired peripheral outline.

Having thus fully described my invention, what I claim as new, and desire to secure by 75 Letters Patent of the United States, is—

An improved article of manufacture consisting of a boot-heel lift having a conical stud shorter than the thickness of the lift inserted from the upper side, leaving a portion of the 80 lift between the lower end thereof and the face of the lift, as and for the purpose set forth.

ELEAZER KEMPSHALL.
